UNITED STATES PATENT OFFICE

WILHELM K. MOLL, OF CHICAGO, ILLINOIS, ASSIGNOR TO DITTO, INC., OF CHICAGO,
ILLINOIS, A CORPORATION OF ILLINOIS

PAPER-STOP DEVICE FOR DUPLICATING MACHINES

Application filed February 18, 1929. Serial No. 340,757.

This invention relates to the art of duplicating machines for producing multiple copies of printed or written matter, and has reference more particularly to machines of this type employing a margin bar equipped with a plurality of spaced stops for arresting and positioning the lower edge of the sheet prior to impressing the latter on the gelatin bed of the machine.

10 In Letter Patent No. 1,753,442, dated April 8, 1930, I have disclosed a duplicating machine more especially designed for billing operations, and wherein the margin bar of the machine is equipped with front, rear and intermediate stops for effecting the correct positioning of the master and copy sheets relatively to the bed prior to the printing operations. In the machine of my aforesaid patent the rearmost stop is a fixed bar at or near 20 the rear edge of the margin bar, the intermediate stop consists of a group of fingers fast on a shaft underlying the margin bar and operating through slots in the latter, the fingers being moved into and out of working 25 position at appropriate times by a ratchet on the shaft and a pawl mounted on the platen carriage; and the front or foremost stop consists of a fixed bar on the front edge of the margin bar. Practical experience in the 30 use of the aforesaid machine has shown that, unless the operator exercises considerable care, the lower edge of a sheet intended to be arrested by the intermediate or rear stop will sometimes catch on and be arrested by the 35 foremost stop.

The primary object of my present improvement is to eliminate this fault; and this I accomplish through a novel front or foremost stop which is shiftable into and out of operative 40 position relatively to the margin bar and is normally held in inoperative position and is automatically shifted to and locked in operative position when its use is required. A still further object of the invention has been 45 to provide a very simple and reliable automatic means for effecting the shifting of the foremost movable stop at the proper times, so that when it is not needed it will lie out of the way of sheets designed to cooperate 50 with a stop in rear thereof.

The invention, in one practical embodiment thereof, is illustrated in the accompanying drawings, in which—

Fig. 1 is a top plan view of the machine; Fig. 2 is an enlarged longitudinal section 55 on the line 2—2 of Fig. 1 through a portion of the bed, the platen carriage, and the margin bar and stop devices, illustrating an idle position of the front stop and a working position of the rotary intermediate stop; 60

Fig. 3 is a fragmentary section illustrating idle positions of the front and intermediate stops;

Fig. 4 is a fragmentary section, illustrating 65 the working position of the front stop and the means whereby said front stop is shifted to working position.

In the machine of my aforesaid patent, I have provided power operated means for actuating the platen carriage over the printing bed, as well as an automatic circuit make and break device for the electric motor operated by the swinging movements of the carriage on its hinge toward and from the printing bed. Some of these last-named mechanisms are shown in Fig. 1, but since the present improvement is not concerned therewith, 70 description of such parts is omitted.

Briefly describing those parts of the machine which immediately cooperate with the 80 subject-matter of the present improvement, 10 designates the usual bed of the duplicating machine that is supported on a suitable upright frame, and 11 designates the usual gelatin apron or band that is movable by 85 the operation of receiving and delivery rollers over the bed 10. 12 designates the flat margin bar that is located opposite and substantially in the plane of the portion of the gelatin band resting on the bed at the front 90 or receiving end of the latter. One of the side frame plates of the machine is formed with laterally extending arms 13, in and between which is mounted a horizontal shaft 14, one of the functions of which is to serve as 95 a guide for the hinge yoke 15 of the platen carriage designated as an entirety by 16. In the carriage 16 is pivotally mounted a rock shaft 17 (Fig. 2) fast on which is a yoke frame 18 carrying a platen roller 19 which 100

serves to roll the sheet out on the duplicating band 11 after the yoke frame 18 has been pushed forwardly and downwardly by a handle 20 thereon. The roll 19 cooperates with a spring-pressed paper-gripping roll 21 to grip the sheet and positively carry it down onto the duplicating band. At the end of the return travel of the carriage the yoke 18 is returned to the raised position shown in Fig. 2 by a spring 22. Mounted on the carriage 16 is an upwardly and forwardly inclined pan 23 that serves to support the sheets as they are positioned on the machine preparatory to impressing them on the duplicating band.

Turning now to a description of those features wherein the present invention more particularly resides, the margin bar 12 is equipped with a rear paper sheet stop consisting of an undercut strip 24 mounted on and transversely thereof; this rearmost stop being identical with the rearmost stop disclosed in my former patent above identified. Journaled in a pair of bearing blocks 25 on opposite sides of and depending from the margin bar 12 is a shaft 26, fast on which is a plurality of suitably spaced discs 27, each of which is formed with a pair of oppositely disposed sector-shaped fingers 28 that, as the shaft 26 is rotated, pass through slots 29 in the margin bar 12, as clearly shown in Fig.

1. At the end of each return travel of the platen carriage, the shaft 26 is given a partial rotation through the agency of a ratchet wheel 30 on one end of the shaft 26 and a pawl 31 mounted on the platen carriage. In the instance shown, the ratchet wheel 30 has six teeth spaced sixty degrees apart; but, of course, the extent of turning movement imparted by the pawl and ratchet is immaterial to the invention, depending upon the particular service designed to be performed by the machine. For example, in a machine employing but two stops on the margin bar used alternately, the ratchet wheel might have four teeth spaced ninety degrees apart.

The slots 29 extend at one end to a point near the front of the margin bar 12, as shown in Figs. 2, 3 and 4, and fast on a shaft 32 journaled in and extending between the forward ends of the blocks 25 is a group of forward stop fingers 33 directly underlying the forward portions of the slots 29 and designed to play through the latter. The shaft 32 is normally urged in a counterclockwise direction by a spring 34 so as to hold the stop fingers 33 below the upper surface of the margin bar 12, as shown in Figs. 2 and 3. Each of the stop fingers 33 is formed with a tail-piece 35 that terminates in a cam 36, the upper end of the latter bearing on the disc 27. When the cam 36 is engaged by the advancing end of either of the stop fingers 28, the fingers 33 are rocked upwardly, as clearly shown in Fig. 4, so that the forward ends of the fingers present themselves in the path of

the sheet of paper drawn downwardly from the pan 23 and serve to arrest the sheet at that point.

The cycle of operation of the device, when embodied in a billing machine of the character disclosed in my former patent aforesaid, is as follows. Assuming that the parts are in the position indicated in Fig. 2, with the platen frame 18 in raised position, a master sheet M is slid down off the pan 23 until its rear edge abuts against and is arrested by the upper stop fingers 28 which at this time are projecting through the slots 29. The carriage is then given a forward and back travel, the master sheet being impressed on the gelatin band during the forward travel and peeled off during the rearward travel. Near the end of the return travel of the carriage, the pawl 31 through the ratchet wheel 30 turns the shaft 26 sixty degrees, shifting the stop fingers 28 to the position shown in Fig. 3 wherein they both lie below the margin bar 12. This movement has not affected the stop fingers 33 because the cam 36 is still engaged with a circular portion of the stop finger disc or hub 27. A copy sheet marked C is next slid down off the pan 23 until its rear end abuts against the rearmost stop 24, as shown in Fig. 3. The platen carriage is then again reciprocated, impressing the copy sheet

on the gelatin bed, and near the end of the return movement of the carriage, the shaft 26 is again stepped forwardly through sixty degrees which brings the stops 28 and 33 to the positions shown in Fig. 4, wherein it will be seen that one of the stop fingers 28 has engaged with the cam 36 and forced the front stop fingers 33 upwardly to working position. The copy sheet is then shifted to a position wherein its rear edge lies against the forward ends of the stop fingers 33, as shown in Fig. 4, and the carriage is again reciprocated to effect a second printing of the copy sheet, and during the return travel of the carriage the shaft 26 is again stepped forwardly another sixty degrees, which restores the parts to the position shown in Fig. 2, thus completing the cycle. As the cam 36 passes off the lower stop finger 28, the spring 34 rocks the shaft 32 counterclockwise, thus returning the foremost stops 33 to the idle position shown in Fig. 2. Of course, the oppositely disposed fingers 28 alternate in performing the sheet stop function.

From the foregoing it will be seen that when a sheet is designed to be arrested by either the rear stop 24 or one of the intermediate stops 28, the foremost stop 33 is below the top surface of the margin bar 12, so that it is impossible that the sheet should be accidentally caught and arrested by the foremost stop when it is intended to be engaged by the intermediate or rear stop.

I claim—

1. In a duplicating machine having a trav-

eling platen carriage, the combination with a margin bar located opposite one end of the printing bed of the machine, of a shiftable paper stop on the front of said margin bar, a second paper stop on said margin bar in rear of said shiftable stop, means normally holding said shiftable stop out of operative position during the functioning of said second stop, and means actuated from the platen carriage for moving said shiftable stop into operative position.

2. In a duplicating machine having a traveling platen carriage, the combination with a slotted margin bar located opposite one end of the printing bed of the machine, of a shiftable paper stop on the front of said margin bar movable through the slot of the latter, a second paper stop on said margin bar in rear of said shiftable stop, a spring normally holding said shiftable stop below the top surface of said margin bar during the functioning of said second stop, and means actuated from the platen carriage for raising said shiftable stop into operative position.

25 3. In a duplicating machine having a traveling platen carriage, the combination with a margin bar located opposite one end of the printing bed of the machine, of a fixed paper sheet stop on the rear of said margin bar, shiftable intermediate and front paper sheet stops also mounted on said margin bar, and means actuated from the platen carriage for moving both of said shiftable stops in predetermined sequence into operative position.

35 4. In a duplicating machine having a traveling platen carriage, the combination with a margin bar located opposite one end of the printing bed, of a fixed paper sheet stop on the rear of said margin bar, shiftable intermediate and front paper sheet stops also mounted on said margin bar, means actuated from the platen carriage for moving said intermediate stop into and out of operative position, a spring normally holding said front stop out of operating position, and means operating synchronously with said intermediate stop moving means for moving said front stop into operative position.

50 5. In a duplicating machine having a traveling platen carriage, the combination with a margin bar located opposite one end of the printing bed, of a fixed paper sheet stop on the rear of said margin bar, shiftable intermediate and front paper sheet stops also mounted on said margin bar, means actuated from the platen carriage for moving said intermediate stop into and out of operative position, a spring normally holding said front stop out of operative position, and means actuated by said intermediate stop for moving said front stop into operative position.

65 6. In a duplicating machine having a traveling platen carriage, the combination

with a slotted margin bar located opposite one end of the printing bed, of a fixed paper sheet stop on the rear of said margin bar, a shaft journaled beneath said margin bar, intermediate stop fingers mounted on said shaft and movable through the slots of said margin bar, a second shaft journaled beneath the front portion of said margin bar, front stop fingers fast on said second shaft registering with the slots of said margin bar, a spring normally holding said front stop fingers below said margin bar, rear extensions on said front stop fingers lying in the paths of said intermediate stop fingers and periodically actuated by the latter to swing said front stop fingers above said margin bar, and means actuated from the platen carriage for intermittently turning said first-named shaft.
